DESIGN FOR A BADGE.

SPECIFICATION forming part of Design No. 17,294, dated May 3, 1887.

Application filed February 21, 1887. Serial No. 228,444. Term of patent 14 years.

To all whom it may concern:

Be it known that I, PETER D. KEYSER, a citizen of the United States, residing in the city and county of Philadelphia, State of Pennsylvania, have invented and produced a new and original Design for a Badge, of which the following is a specification, reference being had to the accompanying illustration, showing the obverse and reverse, and forming part thereof.

10 The leading features of my design for a badge are, first, a star-shaped figure formed of a cross with cautious rays; next, a center on the obverse composed of an encircled eagle; next, a center on the reverse composed of encircled 15 sabers, fasces, liberty cap, an arch of stars, and a laurel wreath, and, finally, a ribbon having stripes peculiarly arranged.

In the accompanying illustration, to which reference is made, A represents a star-shaped 20 figure formed of a cross, a, of eight points, cautious between the sides of the cross with rays b. Within the outlines and on the face of the cross a is the cross c, the outlines of which are parallel with those of the outer cross. At the 25 center of the obverse is a circle, d, within which is a displayed eagle, e. On the circle d, in rilievo, is a motto. The reverse has the star-shaped figure A, similar to the obverse. At the center of the reverse is a circle, f, 30 within which are sabers g, in saltier, surmounted by a fasces, h, palewise, ensigned with the Phrygian cap k and environed with an arch of thirteen stars, m. The points of the sabers are at the base, below which is a wreath of 35 laurel, n. On the circle f, in relief, is a legend.

The badge is pendent from a ribbon, B. The ribbon has a watered appearance, and has stripes representing the national colors of the United States of America.

I claim—

1. A design for a badge having a star-shaped figure composed of an eight-pointed cross cau- 40 tonsed with rays, as shown and described.

4. A design for a badge having a star-shaped figure formed of an eight-pointed cross cau- 55 tonsed with rays, with a center on the obverse composed of an encircled eagle, and a center on the reverse composed of encircled sabers, fasces, liberty cap, an arch of stars, and a laurel wreath, as shown and de- 60 scribed.
